UNITED STATES PATENT OFFICE.

JOHN M. HARGRAVE, OF CINCINNATI, OHIO.

CLAMP.

Application filed July 5, 1927. Serial No. 203,323.

This invention relates to clamps and is particularly directed to the construction of the clamping jaws thereof.

In the type of clamp herein concerned 5 the clamping jaws for engaging the work extend out a considerable distance from the longitudinal connecting bar on which they are mounted. Substantial length for the clamping jaw arms is necessary in order 10 to give the proper clearance for the work being adjusted and clamped between these jaws. The work is clamped between and engages the extreme outer ends of the jaws. When irregular work is clamped between the 15 jaws the work thrusts are often laterally exerted on the jaws so that it is necessary to take care of these torques to prevent distorting of the clamp jaws.

It is the object of this invention to take 20 care of these work strains, torques and thrusts thrown on the outer or work engaging jaw ends through proper disposition of strengthening ribs.

It is another object of this invention to 25 provide a clamping jaw which is light in weight.

Another object is to provide a hollow tubular clamping jaw which is suitably ribbed and reinforced so as to be extremely 30 durable despite decreased weight.

Another object is to so dispose the ribs 35 in the tubular jaw arms that they strengthen against torques resulting from the working thrusts upon the extreme outer ends of the jaws.

Other objects and certain advantages will be more fully set forth in the description of the accompanying drawing forming a part of this specification, in which:

40 Figure 1 is a side elevation of a clamp embodying the present invention.

Figure 2 is a sectional view taken on line 2—2, Figure 1, illustrating in detail the disposition of the ribs and apertures in a 45 jaw.

Figure 3 is a sectional view taken on line 3—3, Figure 2, further detailing the construction of the jaw.

Figure 4 is a sectional view of the jaw 50 taken on line 4—4, Figure 3.

Referring to the drawings, the clamp comprises a longitudinal, rectangular bar 1 and a pair of jaws 2—3 mounted thereon. The type of clamp in which the jaws are used is 55 of little importance in this invention, inasmuch as the invention is directed only to the

construction of a clamping jaw. The jaws are shown assembled in a clamp in order to bring out the direction of torques and thrusts.

Describing the illustrated application of the jaws, jaw 2 is shown as a stationary jaw secured at one end of the longitudinal rectangular bar 1 and jaw 3 as an adjustable jaw sliding longitudinally of the bar in relation to the fixed jaw. The stationary jaw 2 has a screw 4, threaded through the outer end 5 thereof, the screw being disposed parallel to the longitudinal bar.

A wing shaped handle 6 is secured at the 70 outer end of the screw 4 and a flat head 7 is pivoted for universal movement to the other end of the screw as a working engaging element. It is this universal movement which causes lateral thrusts on the screw, these 75 being exerted in twisting strains on the jaw since the screw extends through its outer end of the jaw. The slideable jaw 3 has a faced portion 8 disposed in line with the screw 4. The distance from the line of 80 movement of the screw or the outer ends of the clamping jaws to the bar is somewhat great, in order that large objects may be conveniently manipulated and clamped between the jaws, this necessitating jaws of 85 sufficient tensile strength and properly disposed reinforcing.

As shown in Figures 2, 3 and 4, the jaw is tubular, comprising apertured walls, and 90 interiorly disposed ribs. The ribs 9 are disposed parallel to the bar engaging bore 10 and divide the tubular jaw into a series of 95 cavities 13. These ribs 9 join the four walls of the tubular jaw at numerous points. The inner end wall 12 of the jaw is wider than 100 the body of the jaw so as to provide a bead extending around the entire jaw.

Through each of the cavities 13 formed by the series of ribs 9, pairs of apertures 14 are provided. These apertures 14 are in 100 both side walls 11 of the jaw and are of less dimension than the distance between the ribs. As shown in Figure 2, this dimensioning of the apertures 14 leaves widened outer portions 15 where the ribs 9 join the side walls 105 11 of the jaw. At the outer end of the jaw 8 the metal is thickened as at 16, this providing the raised work engaging portion 8. By this arrangement of apertures and ribs the strains thrown upon the working face 8 are greatly taken up by the side walls of 110 the jaws, through the ribs 9 additionally

strengthening the structure by joining the side walls and solid inner face of the jaw at a series of points. The outer wall 12^a of the jaw is apertured as at 17 entering into each cavity for lightening the structure, these apertures leaving the widened portions 18 where the ribs join the outer wall 12^a.

The various apertures in the walls for 10 lightening the weight of the jaw are disposed so as not to weaken the jaw structure. The leaving of wall portions at the points where the ribs join the side wall adjacent the apertures as at 15 provides eye beam 15 cross sections at these points (see Figure 2) so that the jaws are trussed throughout their length against twisting strains.

By this hollowing out, recessing and ribbing of the jaw, a jaw of greater general 20 thickness is produced without too much weight.

Having described my invention, I claim:

1. A clamp jaw, comprising, a work engaging end, an opposite end having a slide 25 bar engaging bore therein, and a tubular intermediate arm portion having therein a series of ribs disposed parallel to the bar engaging bore.

2. A clamp jaw, comprising, a work-engaging end, a bored slide bar engaging inner end, and an intermediate hollow arm portion having a series of ribs disposed therein parallel to the bar engaging the inner jaw end, and the side walls of said arm portion apertured between the ribs. 30

3. A clamp jaw, comprising, a work engaging end, a slide bar engaging end, and an intermediate arm portion comprising side walls and a series of reinforcing ribs joining said walls. 35

4. A clamp jaw, comprising, a tubular arm portion, a work engaging end and a mounting end, a series of ribs disposed within the arm parallel to the direction of direct load thrust on the jaw outer end and cross-wise in the arm, and the side walls of said arm portion having apertures between the ribs of less width than the distance between said ribs, a portion of said side walls extending out at each side of the ends of the 40 ribs, forming a series of truss points in the jaw structure. 45

In witness whereof, I hereunto subscribe my name.

JOHN M. HARGRAVE.
